UNITED STATES PATENT OFFICE.

DENNIS E. JACKSON, OF CINCINNATI, OHIO.

COMBINED FACE PIECE AND AUTOMATIC VALVE.

Application filed December 30, 1922. Serial No. 610,046.

My invention relates to a combined face piece and automatic valve adapted to be used in all forms of gas anesthesia machines, or other devices in which oxygen or other gaseous substance may be administered to man.

The objects of my invention are to provide a simple, sanitary, safe, convenient, economical, effective, perfect fitting and easily sterilizable face piece adapted to conform to varying sizes and contours of faces; to save expense in the use of oxygen or nitrous oxide or any anesthetic substance which may be administered to the patient; and to provide means whereby oxygen or other gaseous substance may be administered to the patient while at the same time the patient can voluntarily control such administration.

My invention consists in providing a combined face piece and valve for the administration of oxygen, anesthetic substances or other gaseous substances.

My invention also consists in the parts and in the construction, combination and arrangement of parts, as herein set forth and claimed.

In the drawings:

Fig. 1 is a plan view of the device in position for breathing the ordinary air of the surrounding atmosphere;

Fig. 2 is a bottom view of the same;

Fig. 3 is a side elevation showing the device in position upon the face of a patient;

Fig. 4 is a section on the line 4—4 of Fig. 3 showing the operative parts in position which permits the patient to breathe the atmosphere;

Fig. 5 is a similar view showing the operative parts in position to permit the patient to breathe the anesthetic;

Fig. 6 is a section on the line 6—6 of Fig. 1;

Fig. 7 is a plan view of the sponge rubber disk;

Fig. 8 is a plan view of the flexible rubber dam; and

Fig. 9 is a perspective view of the device with the clamp in open position ready to receive the sponge rubber disk and flexible rubber dam.

In the embodiment of my invention as illustrated, and which shows a preferred construction, I provide a conical, oval, dish-shaped shell 1 made of metal or some other substantial material so designed that it will amply fit over or around the face of the

patient, said shell carrying an oval shaped hollow clamp 2 hinged thereto at its rounded end 3 and arranged in such a manner that by opening or closing said clamp an oval shaped disk 4 of sponge rubber or other suitable elastic resilient material, having an elongated central opening 5 therein, may be held firmly in an air-tight position between said clamp and shell. In addition, when arranged for use, said disk is covered with a dam 6 comprising a thin, soft, flexible, elastic membrane made of rubber or other similar material. This rubber dam being very cheap and readily obtainable can be thrown away immediately after use, a new rubber dam being used for the next patient. In adjusting for use said clamp is opened upon its hinge 7 to the position shown in Fig. 9. The heavy sponge rubber disk 4 is placed in position upon the outer inclined flange or rim 8 of the shell and upon this is placed a sheet of thin flexible rubber dam 6, said dam being of slightly larger area than the clamp. The clamp is then closed upon said disk and dam and fastened down tightly by means of two hinged bolts 9 attached to the outer flange of said clamp and adapted to engage in the slots 10 respectively, of two forked projecting ears 11 which extend outwardly from flange 8 of the shell, said bolts each having a wing-nut 12 engaging said ears 11 by which said clamp is tightly drawn and held in position against said dam and disk. When said clamp is thus tightly closed and secured in clamped position the dam is cut, preferably with scissors, longitudinally of its center, forming a slit 13 therein the length of which is so gauged that it will fit the face for which the dam is being prepared, depending upon the size and contour of the patient's face. Said oval disk is of such size and shape as to fit snugly at its edges between the clamp and the flanged edge of the shell. All connections between the oval clamp 2, rubber dam 6, disk 4 and flange 8 of shell 1 are air-tight. The sponge rubber disk 4 is radially slotted around in its central opening in such manner as to form a series of centrally extending and laterally inclined supporting tongues 14 which when the face piece is not being used normally project outwardly beyond the plane of the external surface of the clamp. These tongues by their position are enabled ordinarily to hold the rubber dam in a position extended outwardly from the normal plane of the exterior surface of the

clamp. This arrangement will effect an air-tight connection between the rubber dam and the face 15 of the patient, when the shell is brought down over the face, as shown in Fig. 3, because the projecting tongues of the sponge rubber disk will automatically push the rubber dam outwardly in a direction away from the concavity 16 of the shell and hence cause the dam to conform exactly to and fit tightly against the surface of the patient's face in an area surrounding the nose and mouth. These tongues being flexible and independent of each other will cause the dam to fit comfortably and snugly into all cavities and over all eminences on the patient's face no matter what its general contour may be, as for instance, they will yield or recede inwardly into the cavity of the shell if there is a projecting part of the face which extends inwardly beyond the normal position of the tongues, while if hollows in the face occur as are present at the sides of the nose and in the area over the cheeks, if these be sunken, then the tongues will force the rubber dam to sink down tightly into these depressions. The pressure of the oxygen or gas which is being administered to the patient will always be slightly higher within the face piece than the outside atmospheric pressure. This increased pressure within the face piece will force the flexible rubber dam to fit down tightly against the face in all those areas which are not directly touched by the projecting tongues on the sponge rubber disk. While the disk carrying the centrally projecting tongues is preferably made of sponge rubber, it may, if desired, be made of any other suitable compressible and resilient material.

Connection between the cavity 16 and the shell 1 and an anesthesia machine or other device (not shown) with which the face piece is to be used is made through tube 17 connected to angular tube 18. The tubular passage in the base 19 of the angular or L-shaped tube 18 is of larger bore for a portion of its length to form valve seat 20 at one end and valve seat 21 at the other end the latter being formed by the inner ground end of cup-shaped plug 22 extending into said bore and secured to said base by flange 23 held therein by screws. Tube 18 is made to form connection with an anesthesia machine or other device with which the face piece is being used.

Double faced double acting disk valve 24 is mounted in said enlarged bore and is provided with shank or stem 25 to which is pivotally attached connecting bar 26 at its inner end, said bar being pivotally connected at its outer end to T-arm 27 extending through slot 28 and mounted on pivot 29. Cup-shaped plug 22 is provided with a series of perforations 22'. Headed slidable

plunger 30 is mounted in the end of cup-shaped plug 22 and is held therein by headed screw 31.

Housing 32 is integrally connected to angular tube 18. Within said housing said T-arm 27 is partly disposed and pivotally mounted by means of pivot 29. Projecting hand grasp or hold 33 extends outwardly from said housing, and adjacent thereto is a slot 34 through the housing wall 35 in which hand lever 36 is mounted on pivot 37, and at the inner end of said hand lever an actuating lever 38 is pivotally mounted and is provided with a roller 39 held in constant engagement with the head or cross bar of the T 40 by spring 41 connected at one end to one end of said actuating lever and at the other end to pin 42 mounted in hand lever 36. Spring 43 connected at one end to the housing and at the other end to one edge of hand lever 36 is provided for the purpose of automatically holding hand lever 36 in the position shown in Fig. 4. Hand grasp or hold 33 is provided on its outer end with projecting lug 44, and hand lever 36 is provided upon its outer end with hinged link 45 adapted when said hand lever is drawn to the position shown by Fig. 5, to engage said lug and hold the valve 24 in the position shown in said figure.

Plate 46 covers the system of levers and springs in housing 32, said plate being held in position by screws 47. Angled plate 48 covers the slot-like opening between cup-shaped plug 22 and housing 32, said angled plate being held in position by screws 49. Projecting eye 50 serves as a point of attachment in case it is desired to hang the face piece and valve on a nitrous oxide machine or other device, (not shown), the eye being simply slipped down over a short vertical pin conveniently attached to said machine or device.

As a further matter of convenience the entire valve may be rotated about horizontally in any direction with reference to the shell to which it is attached by means of a hollow, externally threaded and flange-headed bushing 51, the threads of which engage with threads cut in the lower end of tube 17, air-tight connection between the shell and L-shaped valve being constantly maintained by means of gasket 52.

The method of use of the face piece and valve may be described as follows: The face piece is placed over the patient's nose and mouth and gently pressed down until the nose and mouth and part of the chin together with a narrow strip of the surrounding area of the face are all either passed through the slit in the rubber dam 6 and the opening 5 in the sponge rubber disk 4 into the cavity 16 of shell 1, or else are brought into direct contact with rubber dam 6, thereby forming an air-tight connection

between the patient's face and the nitrous oxide machine, or other device, to which the face piece has been attached by means of the L or angular tube.

5 The patient now breathes back and forth through shell 1 and tube 17. From tube 17 there are two routes through either of which the patient may breathe. In the first case, if valve 24 be brought into the position 10 shown in Fig. 5, then the patient can breathe back and forth through shell 1, tube 17 and tube 18, into and out of the rebreathing bag of the nitrous oxide machine or such other device as may be in use at the time. Thus 15 nitrous oxide, oxygen, the vapors of ether, chloroform, ethyl chloride, "somnoform", etc., carbon dioxide or other gaseous substance may be administered to the patient, as desired.

20 In the second case, if valve 24 be brought into the position shown in Fig. 4, then the patient can breathe back and forth through shell 1, tube 17, cup-shaped plug 22, and perforations 22', out into and back from the 25 surrounding atmosphere. In this case the patient breathes air only. But the quick acting system of levers 36, 38, 40, 27 and 26 will produce an instant change in the position of valve 24 when hand lever 36 is moved 30 back and forth. In this manner it is possible for the patient to start to breathe through either of the two possible routes above described, but at any given instant while he is breathing at his usual rate and 35 with ordinary force, hand lever 36 may be shifted from the position shown in Fig. 4 to the position shown in Fig. 5, or in the reverse direction, and this will cause the patient to breathe through the other route. 40 This can be done without any disturbance whatever to the patient and is of special importance when the face piece and valve are used in connection with metabolism devices or other similar types of apparatus.

45 The headed slidable plunger 30 has a special function to perform which may be described as follows. If one uses the face piece with a nitrous oxide machine in which a closed system of anesthesia is used it will 50 be necessary in starting the anesthesia to get rid of the nitrogen which is normally present in the lungs (and blood and tissues) of the patient. This is necessary in order that the space in the lungs which has been 55 previously filled with nitrogen may become filled with nitrous oxide, (plus a small percentage of oxygen to prevent suffocation of the patient). The percentage of nitrous oxide which the patient breathes (in combination with a small amount of oxygen) must be very high, preferably being from 93 to 98 percent, or even greater, in the beginning 60 stages of the anesthesia. To attain this percentage the procedure is carried out as follows: The rebreathing bag is filled with

pure nitrous oxide, and the patient is allowed to inhale this practically pure gas. The valve 24 is held tightly closed against the ground edge 21 of cup-shaped plug 22 during this process. But just as the patient 70 starts to exhale the operator suddenly presses inward on the headed end of slid- able plunger 30. This operation carries headed screw 31 inward against the end of connecting bar 26, thereby pushing bar 26 75 and valve 24 a short distance inward within the tube. This action unseats the valve by pushing it a little distance away from the ground edge 21 of cup shaped plug 22, and this permits a portion of the exhaled nitro- 80 gen, a little of the accompanying oxygen and a small amount of nitrous oxide to pass out through perforations 22' from cup- shaped plug 22 into the surrounding atmos- 85 phere. As soon as the patient ceases to ex- hale the operator withdraws the pressure which he had applied to the head of slid- able plunger 30 and this allows valve 24 to be again closed against ground edge 21 of cup- shaped plug 22, this position being main- 90 tained during the period of the patient's inhalation. In this manner the patient in- hales nearly pure nitrous oxide, but exhales the excess nitrogen (plus some nitrous oxide and a little oxygen) into the surrounding 95 atmosphere. Thus the patient rapidly rids himself of the nitrogen which his lungs (and blood and tissues) contained at the be- ginning of the administration of the nitrous oxide. Meanwhile his lungs have become 100 filled with a very high concentration of nitrous oxide and after a few repetitions of this process the patient will have become sufficiently deeply anesthetized, and will have gotten rid of practically all the ni- 105 tragen which his lungs and tissues previ- ously contained. Thereafter valve 24 is left tightly closed against ground edge 21 of cup-shaped plug 22 until the period of an- 110 esthesia is over. But if at any time the op- erator should admit an excess of oxygen or 115 nitrous oxide to the rebreathing bag, thus causing the patient to breathe against too great a pressure, then valve 24 may be opened for an instant by pressure applied to the head of slidable plunger 30, thus per- 120 mitting escape of a part of the respiratory medium into the surrounding atmosphere, thereby relieving the patient.

125 A further use for this valve and face piece is found in those instances in which patients suffer from a prolonged series of frequently repeated pains of rather brief duration such as occur in obstetrical cases. Under such conditions the attendant fills the 130 rebreathing bag with nitrous oxide. The valve 24 is kept tightly closed with hand lever 36 in the position shown in Fig. 4. The face piece is placed on the patient's face and either held down tightly in position by 135

the patient's left hand, or else is tied down on the patient's face by means of two gauze bandages. So long as the patient feels no pain breathing is carried on through tube 17, cup-shaped plug 22, and perforations 22' into the surrounding atmosphere. But if the patient begins to experience an approaching pain, then with the thumb and fingers of the right hand the patient seizes hand lever 36 and projecting hand grasp 33, and after exhaling as fully as possible out into the surrounding atmosphere as described above, suddenly shifts hand lever 36 from the position shown in Fig. 4 forward into the position shown in Fig. 5. The patient then breathes back and forth into and out of the bag. In a few seconds (before the pain has become severe) the patient will pass into a state of analgesia, or partial or complete unconsciousness, and will thereby cease to suffer from the pain. But when the patient has become sufficiently deeply anesthetized to lose consciousness, there will be a general relaxation of all voluntarily contracted muscles, and the patient will thus involuntarily allow hand lever 36 to be shifted back into the position shown in Fig. 4 by the force of coil spring 43. But when this occurs the patient will suddenly begin to breath back and forth into the surrounding atmosphere, and consciousness will be rapidly regained. The attendant (or operator) will watch in the meantime to see that the rebreathing bag, or other larger container from which the nitrous oxide, or mixture of nitrous oxide and oxygen is being administered to the patient, is refilled as often as may be necessary according to the exigencies of the case. The sudden automatic closing of valve 24 as the patient slowly relaxes hand lever 36 prevents waste or loss of the nitrous oxide or other substance administered to the patient.

My invention is capable of modification in materials, construction and arrangement of parts, as for instance the clamp may be hinged to the shell or otherwise mounted in relation thereto, without departing from the scope or spirit thereof, as defined in the claims.

What I claim as new and desire to secure by Letters Patent is:

1. In a combined face piece and automatic valve, a shell, a clamp hinged thereto, a slotted flexible and resilient disk and a superposed slotted elastic dam interposed between said shell and clamp whereby an air tight joint is formed between said clamp and shell and means to control the medium being respired by the patient substantially as set forth.

2. In a combined face piece and automatic valve, a dish-shaped shell, a hollow clamp hinged thereon, a flexible and resilient rubber disk having a central opening and an

elastic rubber dam superposed thereon and held between said shell and clamp, said shell having a valved passage leading to its concavity.

3. In a combined face piece and automatic valve, a dish-shaped shell having a hollow hinged clamp, a sponge rubber disk having an elongated central opening and having a plurality of laterally inclined tongues extending inwardly around said opening, an elastic covering mounted on said disk, and means for holding said disk and covering between said clamp and shell to form an air tight joint therebetween, said shell having a valved passage connected to its concavity.

4. In a combined face piece and automatic valve, a dish-shaped shell having a valved opening leading to its concavity, a sponge rubber disk mounted on the rim of said shell, an elastic rubber dam mounted on said disk, a clamp hinged to said shell, forked ears on said shell, hinged bolts on said clamp adapted to engage said ears, respectively, and a wing nut on each bolt adapted to engage said ears, respectively, whereby said disk and dam are tightly held between said shell and clamp.

5. In a device of the character described, a sponge rubber disk having a central opening and having supporting tongues projecting into said opening, a dam comprising a thin, elastic, soft, rubber covering superposed on said sponge rubber disk, means for clamping said disk and dam in operative position and said dam having a longitudinal slit in its central portion, for the purposes set forth.

6. In a combined face piece and automatic valve, said face piece having a shell, a straight tube mounted on said shell and communicating with the interior thereof, an angular tube mounted on said straight tube and communicating with the interior thereof, the base of said angular tube having a bore of larger diameter in one end than in its other end to form a valve seat, a double faced valve mounted in said larger bore and having a stem on one side thereof, a connecting bar pivoted to said stem, a cup-shaped perforated and slotted plug mounted and secured in the base of said angular tube whereby the inner end of said plug forms a seat for said double faced valve, a housing attached to said angular tube and having a slot therein registering with the slot in said cup-shaped plug, said housing having a projecting hand hold on its outer wall and having a slot therethrough adjacent to said hand hold, a T-arm pivoted to said housing through its head and pivotally connected to said connecting bar in said plug, a hand lever extending through the slot adjacent to said hand hold and pivoted to said housing, an actuating lever, a roller mounted on said

- actuating lever in engagement with said head, a pin on said hand lever, a spring connecting said pin and said actuating lever whereby said roller is kept in constant engagement with said T-head, and a spring connecting said hand lever and said housing to automatically throw said valve from one position to another when the hand lever is released.
10. 7. In a combined face piece and automatic valve, said face piece having a shell, a straight tube mounted on said shell and communicating with the interior thereof, an angular tube mounted on said straight tube and communicating with the interior thereof, the base of said angular tube having a bore of larger diameter in one end than in its other end to form a valve seat, a double faced valve mounted in said larger bore and having a stem on one side thereof, a cup-shaped plug mounted in said larger bore and forming a valve seat therein and having perforations through its wall and means for operating said valve from one seat to the other.
8. In a combined face piece and automatic valve, a dish-shaped face piece having elastic, resilient face engaging means, a straight tube connected to the interior of said face piece, an L-shaped tube mounted on said straight tube at an angle thereto, the base of said L-shaped tube having a bore in one end thereof larger than in the other end whereby an offset is formed thereby producing a valve seat, a cup-shaped plug adapted to fit in said bore and form a valve seat, means for securing said cup-shaped plug to said base, said cup-shaped plug having its
- wall perforated and slotted, a valve in said base, means for operating said valve to engage either of its seats and a headed sliding plunger adapted to move said valve from one of its seats.
9. In a combined face piece and automatic valve, a face piece having elastic resilient face engaging means, a straight tube connected to the interior of said face piece, an L-shaped tube mounted on said straight tube and communicating therewith, a slotted, perforated and flanged tubular plug extending into and secured to said base, a valve in said base, a connecting bar pivotally connected to said valve, a slotted housing adjacent to said plug, a T-arm pivoted to said bar to move said valve from one seat to the other and a headed slideable plunger adapted to move said valve from one of its seats.
10. In a combined face piece and automatic valve, a face piece having an opening therein adapted to engage the face of a patient, and form air-tight contact therewith, a straight tube, an angular tube, a valve in said angular tube, a cup-shaped slotted and perforated plug mounted in said angular tube, a housing adjacent said angular tube and said plug, operating mechanism mounted in said housing and adapted to operate said valve, a hand lever adapted to actuate said operating mechanism, a handhold on said housing having a lug on the end thereof, and a pivoted link on the end of said hand lever adapted to engage said lug to hold said valve in engagement with its seat formed by the inner end of said cup-shaped plug.

DENNIS E. JACKSON.
